United States Patent

Des. 240,870

Patented Aug. 10, 1976

240,870

DISPLAY STAND

Fred Howard, New York, and Roger G. Ferriter, Yonkers, N.Y., assignors to Hanes Corporation, Winston-Salem, N.C.

Filed May 12, 1975, Ser. No. 576,619

Term of patent 14 years

Int. Cl. D6—04; D20—02

U.S. Cl. D6—24

FIG. 2

FIG. 4

FIG. 1

FIG. 5

FIG. 3

FIG. 1 is a front elevational view of a display stand embodying our new design;

FIG. 2 is a top plan view thereof;

FIG. 3 is a side elevational view thereof;

FIG. 4 is a bottom plan view thereof; and

FIG. 5 is a sectional view taken on line 5—5 of FIG. 1.

I claim:

The ornamental design for a display stand, as shown.
